UNITED STATES PATENT OFFICE.

WILLIAM GARDNER, OF NEW YORK, N. Y.

ALE-PUMP AND ICE-BOX.

SPECIFICATION forming part of Letters Patent No. 298,572, dated May 13, 1884.

Application filed September 21, 1883. (No model.)

To all whom it may concern:

Be it known that I, WILLIAM GARDNER, of the city, county, and State of New York, have invented a new and Improved Ale-Pump and 5 Ice-Box, of which the following is a full, clear, and exact description.

My invention relates to improvements in ale-pumps and ice-boxes; and to this end it consists in the peculiar construction and arrangement of parts, as hereinafter fully described, and pointed out in the claims.

Reference is to be had to the accompanying drawings, forming part of this specification, in which similar letters of reference indicate 15 corresponding parts in all the figures.

Figure 1 is a sectional plan view of my improved ice-box and ale-pump. Fig. 2 is a longitudinal sectional elevation of the same on the line *xx*, Fig. 1, parts being broken out. 20 Fig. 3 is a cross-sectional elevation of the same on the line *yy*, Fig. 1.

The box A is provided in its top with a door, B, which can be hinged or arranged to slide, which door is opened to place the ice in 25 the box, or to place a keg of beer in the box. The front of the box is provided with a hinged or sliding door, C, which can be opened to place a keg of beer that is to be on tap into the box, which door C is provided in its bottom edge with a semicircular recess, C', the bottom of the door opening being provided with a like recess for receiving the spigot. The ice is placed on a metal platform or tray, D, secured to the sides and ends of the box at 30 about the middle of the height of the same. The said tray or platform D does not extend to the ends and sides of the box at all its points, but recesses or openings E are formed between the upturned sides or flanges of the tray and the sides and ends of the box, to permit 35 a circulation of air, which openings can be closed by slides E', (shown in dotted lines,) so that when the slides or dampers are closed all the cold air will be concentrated in the 40 upper air-chambers. If the ale is too cool, the slides are opened, and the temperature of the air thus raised. The rear of the box A is provided with heavy glass panes F, to admit light into the box above and below the ice- 45 platform or tray D. The rear of the box is also provided with an aperture, H, through which a pipe can be passed, which leads from an ice-water receptacle to a cock or spigot on the rear of the box; or the said pipe can be 50 carried around the box to any suitable point,

to facilitate drawing ice-water. Below the ice-tray D the box is provided with a horizontal partition, J, on which bottles, &c., containing liquors, aerated waters, &c., can be placed. Such bottles can also be placed on the floor of 60 the box A, below the horizontal partition J. The ice-tray D is provided with a suitable outlet-pipe, D'. On the inner surface of the box a number of ale-pump cylinders, K, are held, the lower ends of which are connected 65 by pipes L with the several ale-barrels. The upper ends of the cylinders K are provided with tubes M, which project from the front of the box A, and are provided with cocks or faucets N for drawing the ale. The cocks N 70 are held above a drip-tray, O, projecting from the front of the box. In the cylinders K pump-pistons are placed, which can be operated by levers P, pivoted in suitable standards on the top of the box. Any suitable 75 number of pump-cylinders K can be provided. The pump-cylinders K are made of such size that they can hold a considerable quantity of ale, which ale remains in the cylinders for a time, and is cooled by the ice resting on the 80 ice tray or platform D. Kegs of lager-beer, &c., can be placed below the ice-tray D in that portion of the box not occupied by the horizontal partition J. If desired, pump-cylinders K can be arranged at both ends of the 85 box.

Having thus described my invention, what I claim as new, and desire to secure by Letters Patent, is—

1. The combination, with the box A, of the ale-pump cylinders K, secured to one side of the box, and provided with the pipes L at the lower ends, and the pipes M at their upper ends, projecting through the box, and having faucets N, and the lever P, pivoted in suitable supports on the top of the box, and connected to the pump-pistons, substantially as herein shown and described. 90

2. The combination, with the box A, provided with the ice-tray D, having openings 100 E, and slides E', of the pump-cylinders K, provided with the pipes L at their lower ends, and the pipes M at their upper ends, projecting through the box, and having faucets N, and the lever P, connected to the pistons of said 105 pumps, substantially as herein shown and described.

Witnesses: WILLIAM GARDNER.
